UNITED STATES PATENT OFFICE.

CHARLES G. JUSTICE, OF WISE, VIRGINIA, ASSIGNOR OF ONE-HALF TO CHARLES T. KILGORE, OF WISE, VIRGINIA.

RAILROAD-SWITCH-OPERATING DEVICE.

1,263,254.

Specification of Letters Patent. Patented Apr. 16, 1918.

Application filed December 7, 1917. Serial No. 205,959.

To all whom it may concern:

Be it known that I, CHARLES G. JUSTICE, a citizen of the United States, residing at Wise, in the county of Wise and State of Virginia, have invented certain new and useful Improvements in Railroad-Switch-Operating Devices; and I do hereby declare the following to be a full, clear, and exact description of the invention, such as will enable others skilled in the art to which it appertains to make and use the same.

This invention relates to improvements in a switch operating device.

The object of this invention is to improve the construction of a switch operating device and to equip it with novel means whereby the switch may be opened and closed in a quick and reliable manner.

A still further object of this invention is to improve the construction of a switch operating means, and to equip it with novel means whereby should the main line be open a train from the siding may pass out of the siding on to the main line without necessitating the operation of the switch lever for moving the switch point, the switch lever being provided with means for normally retaining the switch point in position after being opened to permit the train to come from the siding on to the main line.

A still further object of this invention is to provide a resilient means connected to the switch operating device, whereby a train passing over the main line will readily move one of the pivoted switch points toward the adjacent rail automatically, and after the train has passed over this point the spring will normally return this switch point to its original position.

A still further object of this invention is to provide a switch operating device of this character, which will be simple, practical and comparatively inexpensive in construction and one that can be manufactured and sold at a low cost.

With these and other objects in view, the invention consists in the novel combination and arrangement of parts hereinafter more fully described and set forth in the claims hereto appended.

In the drawing—

Figure 1 is a top plan view of the switch operating device applied to the usual form of switch point and illustrating the main track open,

Fig. 2 is a perspective view of the slide block,

Fig. 3 is a transverse sectional view taken on the line 3—3 of Fig. 1,

Fig. 4 is a side elevation of the switch operating device as made in accordance with this invention,

Fig. 5 is a sectional view illustrating the manner in which the spring is connected to the slide block,

Fig. 6 is a longitudinal sectional view taken through the switch operating means.

Like numerals of reference designate corresponding parts in all the figures of the drawing.

Referring to the drawing, the numeral 5 designates a plurality of relatively spaced ties of the construction now in general use and have secured thereto the rails 6 and 7 which constitute the main line of a railroad track. A pair of switch points 8 are pivotally secured as at 9 at one end to the upper side of one of the ties between the rails 6 and 7, which switch points are adapted to establish a communication between the main line rails 6 and 7 and the siding rails 10 when in one position and when in the opposite position to close communication between the main line and siding.

The switch points 8 are of the usual construction and are adapted to be operated by a switch operating device designated in its entirety by the numeral 11. The switch operating device comprises a base 12 which has formed integrally with one end an extension 13 secured to the under side of the rails 6 and 7 at a point between a pair of the ties. A switch point supporting rod 14 is secured to the under side of the switch points 8 adjacent the forward ends thereof and extends laterally beyond the main rail 6 and has pivotally secured to said end as at 15 an operating link 16. The operating link has its free end enlarged as at 17 and is provided with a longitudinally extending slot 18, the purpose of which will be hereinafter more fully described.

A slide block 20 is slidably mounted upon the upper side of the base and is provided centrally of its ends with a vertical standard 21, and the ends on opposite sides of the standard are provided with a longitudinally extending slot 22, which slots are adapted to be movable on bolts 23 embedded in the base 12. A standard 24 is secured to the upper

side of the base 12 adjacent the rear end thereof and in direct alinement with the standard 21 of the slide block and the opposing faces of the standards are provided 5 with hooks or eyes 25 to which is secured an expansible coil spring 26, which spring normally tends to hold the slide block in one position and return it to this position after the spring has been expanded. A switch 10 point operating lever 27 has one end pivotally secured by a bolt 28 to the standard 21 of the slide block 20, which bolt is secured in position by any suitable means such as a cotter key or the like.

15 The lever has extending laterally therefrom a bolt 29, which bolt is adapted to pass through a block 30 slidably arranged in the slot 18 of the link 16. A coil spring 31 has one end secured as at 32 to the rear end of 20 the block 30 and its opposite end is secured as at 33 to a bolt 34 which extends vertically through the free end of the link 16, thus it can be seen that should the block be moved toward the inner end of the slot 18 25 of the link, the spring 31 will be expanded and upon releasing of pressure on the link the spring will normally urge the block 30 into its initial position and against the shoulder 35 formed by reducing the slot at 30 the outer end thereof.

The lever 27 is provided with an elongated slot 36 adjacent its outer end and is adapted to be engaged by the standards 37 secured to the upper side of the base 12 so 35 as to hold the lever in either of its positions, which lever when moved to either of its positions is adapted to open or close the communication between the rails 6 and 7 and the siding 10.

40 In operation, if the lever is in the position illustrated in Fig. 1 the communication is then established along the main line by the switch points. Thus it can be seen that a train may be readily run from the siding, 45 and by its flanges engaging one of the switch points 8 it will urge the other switch point 8 over toward the inner side of the rail 7, during which operation the slide block will be moved forwardly in the direction of the rail 7 and the coil spring 26 expanded. Immediately upon the train leaving the siding 10 onto the main rails 6 and 7, the coil spring will act to draw the slide block back to its initial position, thus leaving the main line open.

55 Should the lever be reversed or swung

over toward the rail 6, the switch point 8 will contact with the rail 7, thus opening a communication between the main rails and the siding 10. Should a train be coming 60 down on the main line it would engage the switch point 8 nearest the rail 7, urge the other switch point in the direction of the rail 6 which in turn would move the link 16 which movement would expand the spring 65 31 moving the block 30 rearwardly in the slot 18 of the link and immediately upon the train passing beyond the ends of the switch point, the spring 31 would react to return the switch points to their initial position and thus open a communication between the main tracks 6 and 7 and siding 10. 70

Having thus described my invention, what I claim is:

1. A switch operating device including a 75 base, a slide block mounted upon the base, a switch point operating lever carried by the slide block, a link pivotally secured to the lever, a switch point supporting rod carried by the link, and resilient means 80 carried by the link and slide block to permit of the actuation of the switch points independently of the lever.

2. A switch operating device including a 85 base, a slide block mounted upon the base, a standard carried by the slide block and base, a lever pivotally secured to the standard of the slide block, a link pivotally secured to the lever, a switch supporting rod pivotally secured to the link, and spring means carried by the link and slide block to permit of 90 the operation of the switch point independently of the lever.

3. A switch point operating device comprising a base, a slide block mounted upon 95 the base, standards carried by the slide block and base, a switch point operating lever pivotally secured to the standard of the slide block, a link pivotally secured to the lever, a switch supporting rod pivotally secured to 100 the link, a spring secured to the link and lever, a spring secured to the standards of the slide block and base, said springs permitting of the operation of the switch points by approaching trains independently of the 105 lever.

In testimony whereof I affix my signature in presence of two witnesses.

CHARLES G. JUSTICE.
